LADY'S STOCKING

Walter Mueller, Clifton, N. J., assignor of one-half to Richard E. Schletter, Philadelphia, Pa.

Application July 5, 1951, Serial No. 15,763

Term of patent 14 years

(Cl. D47—7)

To all whom it may concern:

Be it known that I, Walter Mueller, a citizen of the United States, residing at Clifton, in the county of Passaic and State of New Jersey, have invented a new, original, and ornamental Design for a Lady's Stocking, of which the following is a specification, reference being had to the accompanying drawing, forming part thereof, wherein Figure 1 is a side view of a lady's stocking, showing my new design; and Figure 2 is an enlarged view of an area of the high splice portion of the stocking shown in Figure 1.

The opposite side of the stocking is substantially identical with the side depicted in Figure 1. The essential features of the design reside in the portions substantially laterally of the high splice of the stocking.

I claim:

The ornamental design for a lady's stocking, substantially as shown and described.

WALTER MUELLER.
